UNITED STATES PATENT OFFICE.

ADELMER M. BATES, OF CLEVELAND, OHIO, ASSIGNOR TO BATES VALVE BAG COMPANY, OF CLEVELAND, OHIO, A CORPORATION OF WEST VIRGINIA.

MACHINE FOR FILLING VALVE-BAGS.

1,044,475.

Specification of Letters Patent. Patented Nov. 19, 1912.

Application filed May 10, 1909. Serial No. 495,182.

To all whom it may concern:

Be it known that I, ADELMER M. BATES, a citizen of the United States, residing at Cleveland, in the county of Cuyahoga and State of Ohio, have invented a certain new and useful Improvement in Machines for Filling Valve-Bags, of which the following is a specification.

My invention relates to machines for filling bags and has for its object to provide new and improved constructions in machines of that class.

The invention relates more particularly to machines for filling valve bags or other receptacles which have to be filled through a relatively small opening, and contemplates an arrangement for suspending the bags upon filling tubes, which tubes, together with the bags, are connected with scales to measure the proper amount of material.

My invention also contemplates supporting the bag from the top alone instead of giving it the ordinary support at the bottom, although the bags might be so supported and jigged if necessary if the character of the material of which the bags are made or if the material with which they are to be filled should make such a support expedient. I also join the two ideas of partially supporting the bag from the top by means of the tube and supporting it either all or part of the time by means of the jiggling device from the bottom.

My invention has also for its object such further improvements and novel devices as are shown and described in the specification.

The invention is illustrated in the accompanying drawings, wherein—

Figure 1 is a side elevation and part sectional view of my invention showing the bag supported on the scale; Fig. 2 is a similar view showing the adjustable jiggling device to support the bag from the bottom.

Like numbers indicate like parts throughout the drawings.

1 is a hopper or bin containing the material with which the bags are to be filled, this hopper terminating preferably in a cylindrical feeding chamber 2 in which revolves a shaft 3 carrying the preferably curved propeller blades 4, 4. The discharge opening 5 in the feed chamber is controlled by a valve 6. It may be said that any form of feeding device may be used as this forms no part of my present invention.

The bag is supported at the top by a filling tube 7, which extends through its filling opening, and preferably on the sides and back of the cradle 8. The filling tube normally aligns with discharge openings 5, being held against a block 9 on the outside of the filling chamber by the operation of the scale which will be described later. The filling tube is connected with a swinging frame work consisting of two uprights 10, 10. The inner end of the filling tube is attached to a bracket 14 extending from one of the uprights and it projecting from the bottom of the case 11. The cradle is connected with the filling tube by means of the bracket 15. The uprights 10 are riveted to the side of the cradle. It is also associated with some form of weighing apparatus so that the filling tube will be held in alinement with the discharge opening of the filling chamber during the filling operation and will be free to move away from the same when the required quantity of material has been inserted in the bag. For example, in the machine illustrated in the drawings, I provide the lower ends of the uprights 10 with forks 16 which rest upon the knife edges 17 on the scale beams 18, 18 preferably connected together to form a rigid frame work and balanced by the weight 19.

It will be seen that the filling tube is perfectly free to and will move away from the discharge opening in the filling chamber as soon as the gravity of the weight 19 is overcome by the weight of the material in the bag.

The scale beams 18 have each a grooved block 45 supported on the knife edge 46. The weight 19 is hung from a threaded bolt 47 and held in adjustment by nuts 48, 48.

It is important that the vertically movable frame should be held from lateral motion and the filling tubes accurately guided into position in alinement with the discharge opening of the feed chamber. This I accomplish by means of the double scale beam with its engagement with the cradle on each side.

In the mouth of the feed hopper is preferably an agitator consisting of a shaft 50 105 on which are propeller blades 51.

The bag may be held upon the filling tube 7 in any desired manner. For example, I have shown a clip 52 which is pressed against the material of the bag by the cam 110

53 pivoted in a fork 54 on the diagonal brace 14 and provided with a handle 55.

The jiggling device serves on occasion to jig or shake the bag, is set out in Fig. 2 5 wherein 56 is the jiggling board and having the downwardly depending jiggling bar 57 in the sleeve 58, which is mounted on the rock lever 59 fulcrumed on the standard 60. The outer end of this lever has the link 10 61 on the treadle 62, which is fulcrumed at 63. Associated with the lower end of the sleeve 58 is the shaft 64, driven by the belt 65 and carrying the eccentric 66 adapted to operate against the lower end of the 15 bar 57 to oscillate the parts. The operation of the treadle tilts the lever 59 and raises the jiggling device so as to bring it into operative relation to the bag above.

It will be understood that these structures, and particularly those of Fig. 2, are largely diagrammatic.

I do not desire to be limited to the exact details of construction shown or described for obvious modifications will occur to any 25 person skilled in the art and considerable change can be made without departing from the spirit of my invention.

In my claims I shall point out what I specially desire to cover.

30 The use and operation of my invention are as follows: Referring to the jiggling apparatus, it is enough to say that it is arranged so as to be, at the will of the operator, in or out of operation. In many 35 cases it will not be necessary to jig the bag or shake it, as the pressure of the material supplied through the filling tube will be sufficient to thoroughly fill the bag. The bag is shown as without a bottom support 40 except when the jiggling table is brought into operative relation with it. I have therefore here illustrated an intermittently operative top support for the bag for when it is on the jiggling table it is not wholly supported 45 on the tube, an intermittently operative bottom support for a similar reason, an intermittently operative jiggling action, and a separate support for the bag from above and below for under some conditions the

bag would be partially supported from above and partially from below.

Looking at the filling tube, we find that it is a separable filling tube, that it is a movable tube in the sense that it moves with relation to the part from which it is supplied. It is capable, therefore, of disassociation with reference to the feeding apparatus.

I claim:

1. In a bag filling machine the combination, with a filling tube adapted to engage the bag at its top, of means for supporting the bag at the bottom, said means including a jiggling device and means for intermittently bringing said supporting means into operative engagement with the bag independent of the jiggling action.

2. In a bag filling machine the combination of supporting means intermittently operative at both top and bottom of the bag, the bottom supporting means comprising a jiggling device.

3. In a bag filling machine, bag jiggling mechanism comprising a lever, an eccentric roller carried by said lever, means for rotating said roller, a jiggling rod in contact with said eccentric roller, a jig board carried by said rod, means for operating said lever about a fixed point to bring it into opposition to the bottom of the bag.

4. In a bag filling machine means for normally supporting and filling a bag, means for jiggling and supporting the bag during the filling operation and means for positioning the said jiggling means independent of its operating means.

5. In a bag filling machine means for filling and supporting a bag from its top, means for intermittently supporting and jiggling the bag from its bottom and means for 90 positioning said bottom and said jiggling and supporting means independent of the jig operating means.

ADELMER M. BATES.
